PUMP

Anton Rappi, Buffalo, N. Y., assignor to Trico Products Corporation, Buffalo, N. Y.

Application July 27, 1940, Serial No. 347,937

20 Claims. (Cl. 103—4)

This invention relates to a pump for use in the generation of fluid pressure.

The novel fluid displacing means of my invention involves fundamentally the provision of a movable fluid impelling member of novel form in association with a pumping chamber whose interior wall is also of novel form whereby the fluid impelling member and the chamber wall cooperate to provide a plurality of pump chambers which are successively expanded and contracted in size by virtue of movement of the impelling member in the chamber. A primary object of my invention is to provide a fluid displacing pump which will operate in an efficient and continuous manner and one whose construction is practical and economical.

In one form of my invention the casing of the chamber above mentioned is mounted for to and fro movement to permit cooperation between the impelling member and the walls of the pumping chamber in a practical and efficient manner. In such form the casing for the pump chamber itself may comprise a second piston for a second pumping unit, a suitable casing being disposed about such second piston to complete the second pumping unit.

In the specific embodiment of my invention which is depicted in the drawings and described in the ensuing specification the two pumping units referred to are provided with separate valving means whereby the fluids pumped by the two pumping units may be of different characteristic from each other. By the application of mechanical skill the valving arrangement there shown might be modified to merge the streams of fluid pumped by the two pumping units in such manner that their action would be cumulative and supplementary one to the other.

In pumps constructed according to the teachings of my invention the pumping impulses are, comparatively speaking, of relatively small amplitude and high frequency whereby the streams of fluid pumped, whether they be one or two different fluids, are nearly constant in volume and not accompanied by pulsating or surging to the extent that such pulsating and surging is present in pumps heretofore in practical use.

In the drawings:

Fig. 1 is a vertical cross sectional view taken along the axis of rotation of the drive shaft thereof with the wall of the crank case of an internal combustion engine illustrated fragmentarily;

Fig. 2 is a cross sectional view taken generally along line II—II of Fig. 1 but with the rotary driving element in cross section;

Fig. 3 is an end view of the device taken from the left as viewed in Fig. 1 and with portions broken away to better illustrate the fluid passage;

5 Fig. 4 is a cross sectional view taken along the line IV—IV of Fig. 1;

Fig. 5 is a cross sectional view taken along line V—V of Fig. 1;

10 Fig. 6 is a cross sectional view taken approximately along the line 6—6 of Fig. 2;

Fig. 7 is a detailed perspective view of a valving element;

Fig. 8 is a similar view of the opposite side of such valving element; and

15 Fig. 9 is a fragmentary diagrammatic view similar to Fig. 2 but with the elements thereof shown in another phase of cycle of operation.

In the drawings the numeral 10 designates a casing element having a wall 11 and an open side opposite the wall, such open side being normally covered by a closure plate 12 which, with the casing 10, forms a compartment for housing pumping means. Within such compartment there is disposed a piston element 13 which, in 20 the exemplary form, comprises a swinging vane which is pivoted as upon the pin 14 which has its opposite ends supported in the wall 11 of the casing 10 and in the closure plate 12 respectively. It will be noted from a consideration of Fig. 2 that the end of the piston 13 which is adjacent the pivot pin 14 is of relatively short radius struck from the pivot as a center and such end seats against a portion of the casing 10 which has a like curvature to provide a constant seal between the piston 13 and the casing 10 at this point throughout the pivotal movements of the piston.

At its opposite end the piston 13 has a projection 15 whose terminus is likewise arcuate and struck from the center of the pivot pin 14 to engage a similarly curved portion of the interior of the casing 10 so that at this point also the piston is constantly in sealing engagement with the interior of the casing 10. These arcuate engagements together with the fact that the piston 13, in thickness, extends the full distance between the wall 11 of the casing and the closure plate 12, results in the provision of a pair of pump chambers 19 and 20 at opposite sides of the piston as appears in Fig. 2.

50 The piston 13 is adapted, in a manner which will presently appear, to oscillate about the pivot pin 14 to successively and alternately expand and contract the chambers 19 and 20 and suitable means, which will presently be described, are provided for utilizing such alternate expan-

sion and contraction for the pumping of fluid. While a swinging vane type of piston has been shown and described, it will appear that the principles of my invention may be pursued in structures embodying a reciprocating piston or one of any other suitable form.

The medial portion of the piston 13 may be formed with a somewhat bulbous enlargement for the reception of means forming a second distinct but associated pumping unit which may, by suitable modification, be utilized to pump additive quantities of the same fluid as is being pumped by the first pump unit but which, in the illustrated example, is arranged to pump a second and distinct fluid. In the present embodiment of my invention such second pumping unit is utilized for producing alternating movements of the piston 13 for operating the first-described pumping unit. A chamber for such second pumping unit is formed, as appears best in Fig. 2, by providing an opening in the piston or vane 13 as at 24. In the form of the invention which is illustrated, such opening has substantially parallel side walls joined by curving end walls. This description of the shape of the opening 24 is approximately only as will presently appear.

The closure plate 12 is provided with a portion 26 which is disposed substantially centrally thereof and extends in a direction away from the casing 10. The portion 26 cooperates to support the entire pump assembly and, further, provides bearing for a drive shaft 27 for the device. As viewed in Fig. 1, the right-hand end of the shaft 27 is broken away but that end is adapted to be connected with any suitable form of drive means for rotating the shaft 27. In one embodiment the right-hand end of the shaft 27, as viewed in Fig. 1, may be provided with a gear for engagement with a cooperating gear on the camshaft of an internal combustion engine with which the pumping device is associated. The supporting wall 28 which is fragmentarily indicated in Fig. 1 will in such case be a portion of the crank case of such engine.

A fluid displacing element or piston 29 is secured to the shaft 27 for rotation therewith and to this end the displacing element 29 is formed with an opening for receiving the shaft 27, such opening being counterbored to a larger diameter at its left end, as viewed in Fig. 1, for receiving a valving element 33.

The fluid displacing element 29 has a contour which presents three lobes or protuberances which in the illustrated embodiment are equally spaced about the element 29, the intermediate portions of the contour of the element being such that the overall dimension of the element 29 is very nearly constant, considered from various angles in the plane of rotation of the element 29. In one form this end may in general be attained by forming the three equally spaced lobes of relatively small arcs, the side of the element 29 which is opposite each lobe being arcuate and having its center of curvature approximately coincident with the center of curvature of the lobe, although in actual practice certain compensation must be made for the swinging nature of the alternating movement of the piston 13 in the illustrated embodiment.

With the fluid displacing element 29 in the position illustrated in Fig. 2, that is with one of its lobes coinciding with the vertical center line and the other two symmetrically disposed about said center line, the piston 13 which serves as a pump housing for the fluid displacing element 29

is likewise centrally disposed and the pump chambers 19 and 20 which the piston 13 forms with the casing 10 are of equal size, that is they are at midway points in their relative conditions of expansion and contraction. As the fluid displacing element 29 is rotated in a clockwise direction, as viewed in Fig. 2, it will be seen that the lower left-hand lobe of the fluid displacing element 29 will move upwardly and to the left, as seen in that figure, while the lower right-hand lobe will move downwardly and likewise to the left, with the other lobe of that figure moving along the upper curved portion of the contour of the opening 24 in the piston 13. Such movement of the fluid displacing element 29 will cause the piston 13 to move to the left about its pivot 14 until the lower left-hand lobe of Fig. 2 reaches the horizontal center line of the axis of rotation of the fluid displacing element 29 at which time the curved side of the fluid displacing element 29 which lies directly opposite this lobe will be in engagement with the right-hand wall of the opening 24. This position represents the extreme left-hand position of the piston 13 as viewed in Fig. 2 and in this position the pump chamber 19 will be in its state of maximum contraction while the pump chamber 20 will be in its maximum condition of expansion.

Continued rotation of the fluid displacing element 29 will cause the lobe, which appears at the lower left-hand corner of the piston element 31 in Fig. 2, to move upwardly and to the right, while the lobe which is at the top center of the fluid displacing element 29 in Fig. 2 will by this time engage the right-hand side wall of the opening 24 and move downwardly and to the right until it in turn reaches a point where it coincides with the horizontal center line of the axis of rotation of the fluid displacing element 29 at the right-hand side of the opening 24 whereupon the piston 13 will be in its extreme right-hand position and the pump chamber 19 will be fully expanded and the pump chamber 20 fully contracted.

Continuous rotation of the piston element 29 will therefore result in each of the three lobes of the fluid displacing element 29 imparting to the piston 13 both a left and a right-hand movement during each rotation of the fluid displacing element 29 with the result that each pump chamber 19 and 20 will be expanded and contracted to its maximum degree three times during each rotation of the piston element 29, this movement resulting in six complete pump chamber expansion and contraction cycles per revolution of the fluid displacing element 29.

The manner in which these expanding and contracting pumping movements are utilized in the displacement of fluid by the provision of a suitable valve and conduit means for the fluid being pumped will now be described.

An axial bore 30 leads from the left end of the shaft, as viewed in Fig. 1, to a point substantially medially thereof where it meets a transverse opening 31 which registers with a transverse opening 32 in the bearing portion 26. The openings 30, 31 and 32 cooperate to form a fluid discharge passage for the pump chambers 19 and 20 in a manner which will presently appear.

The portion of the shaft receiving opening which is adjacent the counterbore is provided with oppositely disposed notches as at 35. The notches 35 receive a pair of pins 36 which are secured in the shaft 27 adjacent its left end and

radiate from opposite sides thereof. It will be seen that the shaft 27 is to be assembled into the displacing element 29 from the left, as viewed in Fig. 1, to permit introduction of the radiating pins 36 into the notches 35.

Subsequent to the introduction of the shaft 27 into the displacing element 29, the valving element 33 is disposed in the counterbore provided therefor in the displacing element. The valving element 33 is cup-shaped in form and has a pair of protuberances at its rim portion for engagement in the adjacent ends of the notches 35 so that when in assembled position the shaft 27, the displacing element 29, and the valving element 33 rotate as a unit. The cup-shaped valving element is shown in detail in Figs. 7 and 8 and comprises an annular portion 37 and an end wall 38. The protuberances at the rim herefore referred to as engaging in the notches 35 are designated 39 in Figs. 7 and 8.

In assembled relation the outer face of the end wall 38 of the valving element 33 is preferably in the plane of left-hand radial face of the displacing element 29 as viewed in Fig. 1 and rotates therewith. The separability of the shaft 27, the displacing element 29, and the valving element 33 is for convenience in manufacture and assembly only, and functionally they move and act as an integral unit in the embodiment of the invention illustrated in the drawings.

The end wall 38 has three equally spaced fluid passages extending therethrough as at 40, and, in addition, is provided with a blind recess 41 which comprises three divergent arms disposed midway between the several ports 40. No part of the recess 41 extends through the end wall 38 and the radiating arms thereof serve to selectively connect fluid passages formed in the wall 11 of the casing 10 to cooperate in properly valving the pump chambers 19 and 20 in a manner which will now be described.

Fluid communication with the pump chambers 19 and 20 is gained by means of passages 44 and 45 which lead therefrom respectively, and, as appears best in Fig. 3, open respectively in passages 46 and 47 which terminate in ports 48 and 49, respectively. The ports 48 and 49 open into the interior face of the wall 11 of the casing 10. Disposed between the ports 48 and 49 and likewise opening into the inner face of the wall 11 is a port 51 to which may be connected a conduit 52 which will constitute a fluid inlet conduit to the pump chambers 19 and 20.

It has been stated that the valving element 33 rotates with the fluid displacing element 29 and the shaft 27 and it will therefore appear from a consideration of the foregoing description that for a certain period during its rotation a fluid passage 40 of the valve element will pass over and be in communication with the port 48 in the face of the wall 11 and during such period the pump chamber 19 will be connected for exhausting fluid through passages 44 and 46, the port 48, and opening 40, thence through the bore 30 and the transverse element 31 in the shaft 27, and through the opening 32 in the portion 26 of the closure plate 12. Obviously, the valving element 33 will be so related with respect to the displacing element 29 that the foregoing connection between the port 48 and the opening 40 is established during movement of the piston 13 to the left, as seen in Fig. 2, to contract the pump chamber 19.

At the same time the radiating arm of the blind recess 41 which is disposed opposite the

given opening 40 serves to bridge and connect the port 49 and the port 51, the latter of which is connected with a fluid source so that fluid flows into the then enlarging pump chamber 20 through the port 51, the blind recess 41, the port 49 and the passages 47 and 45. Continued rotation of the fluid displacing element 29 and the valving element 33 breaks the stated connections and reverses the connection of the ports 48 and 49 so that they are connected to a source of inlet fluid and with the exhaust passages respectively. It will be noted that the respective inlet and exhaust connections of the chambers 19 and 20 are reversed during every one-sixth revolution of the displacing element 29 to provide for proper valving of the three complete pumping cycles which are executed by each of the pump chambers 19 and 20 during a single rotation of the shaft 27, the fluid displacing element 29, and the valving element 33.

It has already been set forth that the displacing element 29 in the illustrated embodiment, and as is best shown in Fig. 2, is provided with three lobes or projecting portions which are connected by convex faces. The resultant contour is that of a three-lobed cam with the lobes substantially equally spaced about the cam surface and the cooperation of the element 29 as a drive member for the piston 13 has previously been described. As its designation implies, however, the fluid displacing element 29 has a dual function and serves also, in cooperation with the opening 24 of the piston 13, as a second pumping unit. Each convex face of the displacing element 29 cooperates with changing portions of the wall of the opening 24 in the piston element 13 to form a pumping chamber.

With the parts in the position illustrated in Fig. 2, three pumping chambers 55, 56 and 57 are provided. Two pairs of alternately disposed intake and discharge ports 59 and 60 respectively lead from the interior wall of the opening 24 and communicate with intake and discharge passages 61 and 62 respectively which extend through the piston element 13 and terminate at the adjacent face of the closure plate 12. The reverse or non-adjacent side of the closure plate 12 is shown in Fig. 4, but the somewhat rectangular inlet and discharge passages 63 and 64 respectively which extend from the piston engaging face of the closure plate 12 through such closure plate may be seen in Fig. 4 and terminate in variously formed elongate openings numbered 65, 66, 67 and 68. The last mentioned openings are specially formed to cooperate with a discharge fluid and inlet fluid collecting plate 70, shown in detail in Fig. 5, which is provided for merging fluid passing through the two discharge passages 64 and also for merging the fluid passing through the two inlet passages 63 to provide a single ultimate discharge passage and a single ultimate inlet passage adjacent the wall 28 of the internal combustion engine crankcase referred to previously.

To this end, the collecting plate 70 has, in the surface which abuts the closure plate 12, two inlet openings 71 and 72 which communicate respectively with portions of the elongate openings 63 and 66 respectively, which in turn lead from the inlet ports 63. The openings 71 and 72 are merged at the side of the collecting plate, which is away from the closure plate 12, by a depression 74 which is best shown in Fig. 5.

In a similar manner, the face of the collecting plate 70, which is adjacent to the closure plate 12,

is provided with a pair of openings 75 and 76 which register with portions of the elongate openings 65 and 67 respectively which lead from the discharge passages 64. The openings 75 and 76 are also merged at the face of the plate 70, which is away from the closure plate 12, by a depression 77. Fluid inlet and discharge conduits will be associated with the wall 28 of the crank case of the engine in such manner as to communicate with any part of the depressions 74 and 77 respectively.

The casing 10, the closure plate 12, and the fluid collecting plate 70, are held in assembled position with respect to each other with a plurality of screws 80 and the entire assembly may be secured against the wall 28 of an internal combustion engine crank case by means of screws 81.

The operation of the displacing element 29 in the opening 24 of the piston 13 with respect to its fluid displacing function will now be described. The pumping chambers 55, 56 and 57 previously referred to are transitory in their nature and are referred to merely as a convenient starting point in the description of operation. In a sense they come into being and perform a single pumping cycle of intake and exhaust, then cease to exist, giving way to other pumping chambers in the rotation of the displacing element 29 in the chamber 24.

The opening 24 in the piston 13 is developed or generated from the displacing element 29 and is so formed that its opposite side walls, as seen in Fig. 2, are always contacted by the displacing element 29. Either a lobe or an intermediate curving face of the displacing element 29 is always in abutment with each of the approximately straight side walls of the opening 24. Further, each of the three lobes of the displacing element 29 traverses the curving portions at the upper and lower ends of the opening 24 and remains in frictional engagement therewith throughout its travel along both the upper and lower curving portions from one side wall of the opening 24 to the other.

With the displacing element 29 in the position in which it is illustrated in Fig. 2 and rotating in a clockwise direction, the pumping chamber 55 is being enlarged and fluid is being drawn thereinto through the upper left-hand inlet port 59. At the same time the pumping chamber 56 is being contracted and fluid is being expressed therefrom through the upper right-hand exhaust port 60. At this same point in the cycle of operation, the pumping chamber 57 has been filled with fluid through the lower right-hand inlet port 59 and such fluid is being transferred to a point where it will be expressed from the chamber 57 through the lower left-hand exhaust port 60.

Fig. 9 is a diagrammatic view similar to Fig. 2 but with the fluid displacing element 29 in a position 30° in advance of that illustrated in Fig. 2, and it will be noted therefrom that pumping chamber 55 is of greater area than in Fig. 2, the pumping chamber 56 is approaching a state of total exhaustion, the pumping chamber 57 has moved to a position of communication with the lower left-hand exhaust port 60 and fluid is being expressed therefrom, and a new pumping chamber 85 has been created at the lower right-hand portion of the chamber 24 and is in communication with the lower right-hand inlet port 59 and drawing fluid therethrough.

As the approaching lobe of the displacing element 29 reaches the upper right-hand exhaust

port 60, the pumping chamber 56 is in a state of total exhaustion and in fact ceases to exist, giving place to the new pumping chamber 85. In subsequent rotation of the displacing element 29, the pumping chamber 57 is likewise totally compressed when the next succeeding lobe of the displacing element 29 reaches the lower left-hand port 60, in turn giving way to a new pumping chamber which forms at the upper left-hand intake 59 in the same manner as in the case of the pumping chamber 85. It will be noted from the foregoing that at some periods in the cycle of rotation of the displacing element 29 in the opening 24, there are three active pumping chambers and at other times four, the latter being the case whenever a curved side of the displacing element 29, as distinguished from a lobe, is in engagement with one of the straight side walls of the opening 24.

In the form of the invention which is described herein, the pump formed by the displacing element 29 and the chamber 24 and the pump formed by the piston 13 and the casing 10 co-operate mutually and contribute each to the performance of the other in that the portion of the oil which is the medium being pumped by the displacing element 29 is forced through a groove 87 formed in the face of the piston 13 which is adjacent the wall 11 of the casing 10, such oil traveling along the bearing of the pivot pin 14 and subsequently outward through a groove 88 formed in the opposite face of the piston 13 whereupon the oil serves to lubricate and provide a fluid seal for the piston 13 at its opposite point of arcuate engagement with the casing 10.

The exhaust passages 62 extend entirely through the piston 13 and at the wall 11 of the casing 10 intersect a circular oil groove 90 formed in the face of the piston 13 to further assist in the provision of an oil seal for the pumping unit formed by the piston 13 and the casing 10. The inlet passages 61 stop short of the wall 11 of the casing 10 to prevent withdrawal of sealing lubricant therefrom. In the embodiment illustrated in the drawings the external pumping unit comprising the piston 13 and the casing 10 is used to create a partial vacuum, usually for the operation of the automotive accessories, and the air pumped thereby is exhausted into the internal combustion engine crank case. In this way sealing lubricant which passes from the oil pumping unit to the air pumping unit is ultimately returned to the engine crank case.

Various modifications may be made in the structure which is described by way of example without departing from the spirit or scope of the invention which is to be considered as limited only by the appended claims.

I claim:

1. In a fluid pump, a casing having an opening therein comprising a continuous non-circular wall, a rotatable piston comprising a cam-like element disposed in said opening for rotation therein on an axis coincident with its geometric center and having three lobes, the wall of said opening being so formed that the three lobes of the piston are substantially permanently in contact with said wall during rotation of said piston to form a plurality of pumping chambers, means permitting limiting body movement of said casing but preventing rotation thereof, said casing being formed with inlet and exhaust passages, the rotation of said piston being adapted to successively expand said pumping chambers in the region of the inlet

passages and contract said pumping chambers in the region of the exhaust passages to pump fluid in a substantially continuous flow.

2. In a fluid pump, a casing having an opening therein comprising a continuous non-circular wall, a rotatable piston therein comprising a cam-like element disposed in said opening for rotation therein about a fixed axis and having three lobes, the continuous wall of said opening forming a closed figure having substantially parallel side wall portions and curving end wall portions connecting the side wall portions, said casing being mounted for guided movement transversely to said parallel side wall portions and said opening being so shaped and proportioned with respect to the lobes of the piston that the three lobes of the piston are substantially permanently in contact with said wall during rotation of said piston to form a plurality of pumping chambers, said casing being formed with inlet and exhaust passages, the rotation of said piston being adapted to successively expand said pump chambers in the region of the inlet passages and contract said pumping chambers in the region of the exhaust passages to pump fluid in a substantially continuous flow.

3. In a fluid pump, a casing having an opening therein comprising a continuous non-circular wall, a rotatable piston therein comprising a cam-like element disposed in said opening for rotation therein on an axis coincident with its geometric center and having three arcuate lobes and three arcuate sides connecting the lobes with the radius of each lobe and the radius of the side opposite such lobe approximately concentric, said casing being formed that the three lobes of the piston are substantially permanently in contact with said wall during rotation of said piston to form a plurality of pumping chambers, means permitting limited body movement of said casing but preventing rotation thereof, said casing being formed with inlet and exhaust passages, the rotation of said piston being adapted to successively expand said pump chambers in the region of the inlet passages and contract said pumping chambers in the region of the exhaust passages to pump fluid in a substantially continuous flow.

4. In a fluid pump, a casing having an opening therein comprising a continuous non-circular wall, a rotatable piston therein comprising a cam-like element disposed in said opening for rotation therein and having three lobes, the continuous wall of said opening forming a closed figure having substantially parallel side wall portions and curving end wall portions connecting the side wall portions and the piston having three arcuate lobes and three arcuate sides connecting the lobes with the radius of each lobe and the radius of the side opposite such lobe approximately concentric, said casing being mounted for guided movement transversely to said parallel side wall portions and said opening being so shaped and proportioned with respect to the lobes of the piston that the three lobes of the piston are substantially permanently in contact with said wall during rotation of said piston to form a plurality of pumping chambers, said casing being formed with inlet and exhaust passages, the rotation of said piston being adapted to successively expand said pump chambers in the region of the inlet passages and contract said pumping chambers in

the region of the exhaust passages to pump fluid in a substantially continuous flow.

5. In a fluid pump, a casing having an opening therein comprising a continuous non-circular wall, a rotatable piston therein comprising a cam-like element disposed in said opening for rotation therein on an axis coincident with its geometric center and having a plurality of lobes of odd number, the continuous wall of said opening forming a closed figure having substantially parallel side wall portions and curving end wall portions connecting the side wall portions and the piston having arcuate lobes and arcuate sides connecting the lobes with the radius of each lobe and the radius of the side opposite such lobe approximately concentric, said casing being mounted for guided movement transversely to said parallel side wall portions and said opening being so shaped and proportioned with respect to the lobes of the piston that the lobes of the piston are substantially permanently in contact with said wall during rotation of said piston to form a plurality of pumping chambers, means supporting said casing for limited body movement but preventing rotation thereof, said casing being formed with inlet and exhaust passages, the rotation of said piston being adapted to successively expand said pump chambers in the region of the inlet passages and contract said pumping chambers in the region of the exhaust passages to pump fluid in a substantially continuous flow.

6. In a fluid pump, a movably mounted pump casing, a piston rotatable on an axis coincident with its geometric center comprising a cam having three lobes, said casing having an opening therein having a continuous non-circular wall, said rotatable piston being disposed in said opening for rotation therein, said opening being so formed that the three lobes of said piston are substantially permanently in contact with said wall during rotation of said piston to form a plurality of pumping chambers, said wall being formed with inlet and exhaust passages, the rotation of said piston being adapted to successively expand said pumping chambers in the region of the inlet passages and contract said pumping chambers in the region of the exhaust passages to pump fluid in a substantially continuous flow.

7. In a fluid pump, a casing and a piston disposed for to and fro movement therein, fluid conduit means for communication with the interior of said casing at opposite sides of said piston and valve means for controlling such communication, and a second pump comprising an opening formed in said piston and having a continuous non-circular wall, and a rotatable piston comprising a cam-like element having three lobes, the continuous wall of said opening being so formed that the three lobes of said rotatable piston are substantially permanently in contact with said wall during rotation of said piston to form a plurality of pumping chambers and to impart to and fro movement to said first mentioned piston during rotation of the rotatable piston, the first mentioned piston being formed with inlet and exhaust passages for said second pump, the rotation of said rotatable piston being adapted to successively expand said pumping chambers in the region of the inlet passages and contract said pumping chambers in the region of the exhaust passages.

8. In a fluid pump, an oscillatable casing having an opening therein comprising a contin-

uous non-circular wall, a rotatable piston therein comprising a cam-like element disposed in said opening for rotation therein and having three lobes, the continuous wall of said opening forming a closed figure having substantially parallel side wall portions and curving end wall portions connecting the side wall portions, said casing being oscillatable in a direction transverse to said side wall portions and said opening being so shaped and proportioned with respect to the lobes of the piston that the three lobes of the piston are substantially permanently in contact with said wall during rotation of said piston to form a plurality of pumping chambers, said casing being formed with inlet and exhaust passages, the rotation of said piston being adapted to successively expand said pump chambers in the region of the inlet passages and contract said pumping chambers in the region of the exhaust passages to pump fluid in a substantially continuous flow.

9. In a fluid pump, an oscillatable casing having an opening therein comprising a continuous non-circular wall, a rotatable piston therein comprising a cam-like element disposed in said opening for rotation therein and having a plurality of lobes of odd number, the continuous wall of said opening forming a closed figure having substantially parallel side wall portions and curving end wall portions connecting the side wall portions and the piston having arcuate lobes and arcuate sides connecting the lobes with the radius of each lobe and the radius of the side opposite such lobe approximately concentric, said casing being oscillatable in a direction transverse to said parallel side wall portions and said opening being so shaped and proportioned with respect to the lobes of the piston that the lobes of the piston are substantially permanently in contact with said wall during rotation of said piston to form a plurality of pumping chambers, said casing being formed with inlet and exhaust passages, the rotation of said piston being adapted to successively expand said pump chambers in the region of the inlet passages and contract said pumping chambers in the region of the exhaust passages to pump fluid in a substantially continuous flow.

10. In a fluid pump, a casing and means mounting said casing for limited pivotal movement about a fixed axis, said casing having an opening therein comprising a continuous non-circular wall, a piston rotatable about a fixed axis and comprising a cam-like element disposed in said opening for rotation therein and having three lobes, the wall of said opening being so formed that the three lobes of the piston are substantially permanently in contact with said wall during rotation of said piston to form a plurality of pumping chambers, said casing being formed with inlet and exhaust passages, the rotation of said piston being adapted to successively expand said pump chambers in the region of the inlet passages and contract said pumping chambers in the region of the exhaust passages to pump fluid in a substantially continuous flow.

11. In a fluid pump, a casing and means mounting said casing for limited pivotal movement about a fixed axis, said casing having an opening therein comprising a continuous non-circular wall, a piston therein rotatable about a fixed axis and comprising a cam-like element disposed in said opening for rotation therein

and having three lobes, the continuous wall of said opening forming a closed figure having substantially parallel side wall portions and curving end wall portions connecting the side wall portions and the piston having three arcuate lobes and three arcuate sides connecting the lobes with the radius of each lobe and the radius of the side opposite such lobe approximately concentric, said opening being so shaped and proportioned with respect to the lobes of the piston that the three lobes of the piston are substantially permanently in contact with said wall during rotation of said piston to form a plurality of pumping chambers, said casing being formed with inlet and exhaust passages, the rotation of said piston being adapted to successively expand said pump chambers in the region of the inlet passages and contract said pumping chambers in the region of the exhaust passages to pump fluid in a substantially continuous flow.

12. In a fluid pump, a casing and a rotatable piston therein, said casing having an opening for receiving said piston, said opening, as viewed along the axis of rotation of the piston, having substantially parallel side wall portions and curving end wall portions connecting said side wall portions to form an uninterrupted wall surface, said casing being mounted for movement in a direction transverse with respect to said parallel side wall portions, said rotatable piston having three lobes, said opening and said piston being so proportioned that the three lobes are adapted to traverse said uninterrupted wall surface in substantially continuous contact therewith, said lobes cooperating with said wall surface to form pump chambers between successive lobes, and inlet and exhaust passages formed in said casing and communicating with said pump chambers in the region of their successive expansion and contraction.

13. In a fluid pump, a casing and a piston disposed therein, means mounting said piston for pivotal rocking movement about a fixed axis, fluid conduit means for communication with the interior of said casing at opposite sides of said piston and valve means for controlling such communication, and a second pump comprising an opening formed in said piston and having a continuous non-circular wall, and a rotatable piston comprising a cam-like element having three lobes, the continuous wall of said opening having parallel side wall portions engageable by said rotating piston to impart alternating pivotal movement to said first mentioned piston, said rotatable piston and said opening being so formed that the three lobes of the piston are substantially permanently in contact with said wall during rotation of said piston to form a plurality of pumping chambers, the first mentioned piston being formed with inlet and exhaust passages, the rotation of said rotatable piston being adapted to successively expand said pump chamber in the region of the inlet passages and contract said pumping chambers in the region of the exhaust passages.

14. In a fluid pump, a casing having an opening therein comprising a continuous non-circular wall, a rotatable piston comprising a cam-like element disposed in said opening for rotation therein on an axis coincident with its geometric center and having three lobes, the wall of said opening being so formed that the three lobes of the piston are substantially permanently in contact with said wall during rota-

tion of said piston to form a plurality of pumping chambers, means supporting said casing for guided to and fro movement by engagement of the lobes of the piston with the wall of said opening, said casing being formed with inlet and exhaust passages, the rotation of said piston being adapted to successively expand said pumping chambers in the region of the inlet passages and contract said pumping chambers in the region of the exhaust passages to pump fluid in a substantially continuous flow.

15. In a fluid pump, a casing having an opening therein comprising a continuous non-circular wall, a rotatable piston comprising a cam-like element disposed in said opening for rotation therein on an axis coincident with its geometric center and having three lobes, said opening having substantially parallel side wall portions and curving end wall portions connecting said side wall portions to form a substantially uninterrupted wall surface and said opening being so formed that the three lobes of the piston are substantially permanently in contact with said wall during rotation of said piston to form a plurality of pumping chambers, means supporting said casing for guided to and fro movement by engagement of the lobes of the piston with the side walls of said opening, said casing being formed with inlet and exhaust passages, the rotation of said piston being adapted to successively expand said pumping chambers in the region of the inlet passages and contract said pumping chambers in the region of the exhaust passages to pump fluid in a substantially continuous flow.

16. In a fluid pump, a casing having an opening therein comprising a continuous non-circular wall, a rotatable piston comprising a cam-like element disposed in said opening for rotation therein on an axis coincident with its geometric center and having three lobes, the wall of said opening being so formed that the three lobes of the piston are substantially permanently in contact with said wall during rotation of said piston to form a plurality of pumping chambers, means supporting said casing for oscillation by engagement of the lobes of the piston with the wall of said opening, said casing being formed with inlet and exhaust passages, the rotation of said piston being adapted to successively expand said pumping chambers in the region of the inlet passages and contract said pumping chambers in the region of the exhaust passages to pump fluid in a substantially continuous flow.

17. In a fluid pump, a casing having an opening therein comprising a continuous non-circular wall, a rotatable piston comprising a cam-like element disposed in said opening for rotation therein on an axis coincident with its geometric center and having three lobes, said opening having substantially parallel side wall portions and curving end wall portions connecting said side wall portions to form a substantially uninterrupted wall surface and said surface being so formed that the three lobes of the piston are substantially permanently in contact with said wall during rotation of said piston to form a plurality of pumping chambers, means supporting said casing for oscillation by engagement of the lobes of the piston with the wall of said opening, said casing being formed with inlet and exhaust passages, the rotation of said piston being adapted to successively expand said

pumping chambers in the region of the inlet passages and contract said pumping chambers in the region of the exhaust passages to pump fluid in a substantially continuous flow.

- 5 18. In a fluid pump, a casing mounted for guided to and fro movement, a rotatable piston comprising a cam-like element having three lobes, said casing having an opening receiving said piston for rotation therein, the wall of said opening having opposed side walls spaced a distance equal to the greatest diametrical dimension across said piston whereby said casing is moved to and fro by rotation of said piston therein, the end walls of said opening being generated by the movement of the piston lobes therealong during the to and fro movement of said casing, whereby the three lobes of the piston are substantially permanently in contact with said wall during rotation of said piston to form a plurality of pumping chambers, said casing being formed with passages for taking in and exhausting fluid, the rotation of said piston being adapted to successively expand and contract said pumping chambers to pump fluid in a substantially continuous flow.

- 15 19. In a fluid pump, a rotatable piston comprising a cam-like element having three lobes, a casing having an opening receiving said piston for rotation therein and having a pivot spaced from said opening to permit oscillation of said casing, the wall of said opening having opposed side walls spaced a distance equal to the greatest diametrical dimension across said piston whereby said casing is moved to and fro by rotation of said piston therein, the end walls of said opening being generated by the movement of the piston lobes therealong during the to and fro movement of said casing, whereby the three lobes of the piston are substantially permanently in contact with said wall during rotation of said piston to form a plurality of pumping chambers, said casing being formed with passages for taking in and exhausting fluid, the rotation of said piston being adapted to successively expand and contract said pumping chambers to pump fluid in a substantially continuous flow.

- 20 20. In a fluid pump, a casing mounted for guided to and fro movement, a rotatable piston comprising a cam-like element having three arcuate lobes and three arcuate sides connecting the lobes with the radius of each lobe and the radius of the side opposite such lobe approximately concentric, said casing having an opening receiving said piston for rotation therein, the wall of said opening having opposed side walls spaced a distance substantially equal to the sum of the said two radii whereby said casing is moved to and fro by rotation of said piston therein, the end walls of said opening being generated by the movement of the piston lobes therealong during the to and fro movement of said casing whereby the three lobes of the piston are substantially permanently in contact with said wall during rotation of said piston to form a plurality of pumping chambers, said casing being formed with passages for taking in and exhausting fluid, the rotation of said piston being adapted to successively expand and contract said pumping chambers to pump fluid in a substantially continuous flow.
